UNITED STATES PATENT OFFICE.

KARL WIESER, OF RÜTTENSCHIED, NEAR ESSEN-ON-THE-RUHR, GERMANY,
ASSIGNOR TO FRIED. KRUPP, OF ESSEN-ON-THE-RUHR, GERMANY.

PERCUSSION-FUSE FOR EXPLODING SHELLS.

SPECIFICATION forming part of Letters Patent No. 744,448, dated November 17, 1903.

Application filed September 21, 1901. Serial No. 76,019. (No model.)

To all whom it may concern:

Be it known that I, KARL WIESER, a citizen of the German Empire, residing at 34 Fried-erikenstrasse, Rüttenscheid, near Essen-on-the-Ruhr, Germany, have invented certain new and useful Improvements in Percussion-Fuses for Exploding Shells, of which the following is a specification.

This invention has reference to improvements in percussion-fuses for exploding shells, and has for its object to provide means within said fuses whereby the ignition of the bursting charge of the shell can be so controlled as to cause the explosion of the shell either at the instant of impact or after it has penetrated into or passed through the target.

With this object in view my invention consists, essentially, in a percussion-fuse for shells having two connections between its percus-
sion-chamber and the bursting charge of the shell, the one of which connections is substantially direct between the said chamber and the bursting charge, while the other connection has an interposed slow-burning mass, and means whereby the direct connection between the percussion-chamber and the bursting charge can be closed off to cause retardation of explosion.

The nature of this invention will best be understood when described in connection with the accompanying drawings, in which—

Figure 1 represents a central section of one form of projectile embodying my invention, part of the body of the shell being broken away and the parts being in position for direct connection between the percussion-chamber and the bursting charge. Fig. 2 is a similar view showing the parts in position for slow ignition. Figs. 3 and 4 are sectional views similar to Figs. 1 and 2, illustrating a modified form.

Similar letters of reference designate corresponding parts throughout the several views of the drawings.

Referring at present to Figs. 1 and 2 of the drawings, the letter A designates the needle-bolt; B, the check-ring; C, the safety-spring, and D the fulminate, all of which are placed within a case E, arranged within the body F of the fuse. The case E can be rotated within the central bore of the fuse-body and carries

an annular flange e. The outer end of the case is closed by a screw-plug which contains the fulminate D previously mentioned, and said case is held against shifting by a collar G, screwed into the body F, engaging a shoulder on the annular flange e. In the bottom of the case E is formed an oblique channel H, having its inner mouth or discharging end eccentrical with respect to the longitudinal axis of the fuse. Beneath the case E there is inserted a plug K, which extends contiguous with the case and is prevented from turning by any suitable means and contains two channels L and M, one of which—for instance, the channel M—is provided with a charge of slow-burning powder. By turning the case E the channel H can be brought into a position either to effect communication of the percus-
sion-chamber of the fuse with the channel L, as shown in Fig. 1, or with the channel M, as shown in Fig. 2. A disk N, of cloth or other suitable material, is placed between the case E and the insertion-piece K, said disk serving as a packing and being provided with two perforations corresponding to the channels L and M. Both the channels L and M are directed toward a channel O, passing through the bottom of the fuse and enlarged toward the insertion-piece K for the reception of a quick-burning charge, the latter also being provided with a longitudinal channel. This charge is intended simply to increase the fire-jet from the igniter and to positively insure firing of the bursting charge.

To enable the case E to be conveniently turned by means of a key and to lock it in either of the desired positions, the following provisions are made. The flange e of the case E is provided with diametrically opposite perforations located at equal distances from the center of the case, and each of these perforations has an inner and outer part connected by a neck of smaller diameter than the other parts. The outer parts of the perforations p serve for the insertion of the corresponding pins of a suitable key, while the lower parts have loosely inserted therein pins P. The outer ends of the pins P are of reduced diameter, so as to loosely fit the bore between the inner and outer parts of the perforations p. In a hole of the body F of the

fuse a spring-bolt Q is so placed as to be capable of entering one or the other of the perforations *p* when the respective perforation is brought opposite to the bolt Q by turning 5 the case by means of the key, thereby locking the case against further turning. At the same time this bolt Q forces the corresponding pin P outwardly, so that its upper thinner part projects into the perforation *p* into the 10 path of the key in such a position that when the key is inserted said pin is depressed and through it the bolt Q, thus unlocking the case and permitting the same to be turned.

In Fig. 1 the case E is shown in the position 15 when the channel II connects with the open channel L, so that when by the impact the firing-pin sticks the fulminate, as usual, the fire-jet passes without obstruction through the bore of the needle-bolt and the channels 20 L and O to the bursting charge, causing the charge to explode the moment the shell strikes. If, however, it is desired to retard the action, the case is unlocked by inserting the key, and by turning the latter one hundred 25 and eighty degrees the parts are brought into the relative positions shown in Fig. 2. The proper positions of the parts are indicated by marks on the upper ends of the case and on the body of the fuse. (Not shown.) 30 When now the key is removed, the spring-bolt Q is forced into the second perforation *p* of the case. In this position of the case the channel II terminates over the channel M of the insertion-piece K, which channel is filled 35 with slow-burning powder, so that the bursting charge is not ignited until this powder mass is burned—that is, ignition of the bursting charge is retarded.

In the modification shown in Fig. 3, the 40 needle-bolt A, the check-ring B, and the safety-spring C are arranged directly within a bore of the fuse-body F, while the fulminate D is inserted within the recess of the screw-cap closing said bore. From the percussion- 45 chamber two separate paths lead to the inside or charge of the shell. One of these paths is formed by an oblique channel R, leading to a longitudinal channel S, parallel to the axis of the fuse. This channel S extends to the 50 head of the fuse-body and can be filled up by a screw-bolt V. At its bottom the channel S receives a powder charge, reinforcing the action of the fire-jet from the fulminate, said charge consisting of quick-fire powder and 55 being in direct connection with a bore T of the fuse-body, which itself is closed by a screw-plug with a longitudinal bore O and is likewise filled with a charge of quick-fire powder perforated longitudinally and cross- 60 wise. The second connection between the percussion-chamber and the interior of the shell is formed by the channel U, which is filled by slow-fire powder and leads to the bore T.

When the shell is to be exploded without 65 delay by this fuse, the screw-bolt V is removed, Fig. 3. The fire-jet then passes through the channels R, S, T, and O and ex-

plodes the charge before the slow-fire powder mass in the channel U is completely burned. When, however, the explosion is to be delayed and not to take place until the shell has penetrated into the target, the channel S is filled up by the insertion of the screw-bolt V, Fig. 4, so that the ignition of the bursting charge cannot take place until after the slow-fire powder mass in the channel U has burned through to the channel T.

As may be readily seen, the above-described arrangements may also be used for such percussion-fuses as are combined with a time fuse into a combination-fuse without materially changing the nature of the invention. The closing up of the direct connection between the fire-space of the percussion-fuse and the bursting charge may also be effected 85 by other means than those shown and described.

What I claim as new is—

1. In a percussion-fuse for shells the combination of two connections between the percussion-chamber of the fuse and the bursting charge of the shell, one of which connections is substantially direct between the said chamber and the bursting charge while the other connection has an interposed slow-burning 95 mass, and manually-adjusted means whereby the direct connection between the percussion-chamber and the bursting charge can be closed off to cause retardation of explosion, substantially as described.

2. In a percussion-fuse for shells the combination of two interchangeable channels between the percussion-chamber of the fuse and the bursting charge of the shell, one of which channels is substantially direct between the 105 said chamber and the said charge while the other channel has an interposed slow-burning mass, and a manually-adjusted rotary case placed within the body of the fuse and adapted to connect the percussion-chamber with one channel or the other, substantially as described.

3. In a percussion-fuse for shells the combination of two interchangeable channels between the percussion-chamber of the fuse and the bursting charge of the shell, one of which channels is substantially direct between the 115 said chamber and the said charge while the other channel has an interposed slow-burning mass, a rotary case placed within the body of 120 the fuse and adapted to connect the percussion-chamber with one channel or the other, and means for locking said case in both positions, substantially as described.

4. In a percussion-fuse for shells the combination of two interchangeable channels between the percussion-chamber of the fuse and the bursting charge of the shell, one of which channels is substantially direct between the 125 said chamber and the said charge while the other channel has an interposed slow-burning mass, a rotary case placed within the body of the fuse and adapted to connect the percussion-chamber with one channel or the other,

means for locking said case in both positions, and a key for unlocking and turning the case, substantially as described.

5. The combination with the primer, of a slow-burning charge, a direct channel, and manually-operated means for directing the flame from the primer through the direct channel or through the slow-burning charge.

6. In a fuse, the combination with a primer, 10 and means for delaying the action of the fuse, of a rotatable device provided with a passage-way arranged to be moved into line between the primer and the explosive charge to cause an instantaneous explosion and to be moved 15 to another position to direct the ignition through the delay-action device.

7. In a fuse, the combination with a primer, and means operated by the impact of the projectile for detonating the primer, of a bursting 20 charge arranged to be exploded by the primer, a slow-burning charge, and manually-adjustable means directing the ignition-flame through the slow-burning charge to cause a delayed explosion and through another passage to cause an instantaneous explosion.

8. The combination with the primer, the delay-action device and the direct channel, of manually-operated means for opening and 30 closing the direct channel.

9. The combination with a fuse having a percussion-chamber, a ignition-channel leading from the percussion-chamber to the bursting charge of the shell, and a slow-burning 35 charge arranged in said channel, of a channel around said slow-burning charge, and manually-adjusted means for opening and

closing the second channel as a passage for the ignition.

10. A combined instantaneous and delay-action fuse, having means for starting ignition, a channel for conducting ignition to the exploding charge, a second channel for conducting ignition to the exploding charge, a slow-burning substance in one of said channels, and manually-adjusted means causing the ignition to pass by way of the slow-burning charge, at will. 40 45

11. In a fuse, the combination of a priming device, means for delaying the action of the fuse interposed between the priming device and the bursting charge, a direct channel and hand-operated means for exposing the direct channel to, and for isolating it from, the fire-flash of the priming device. 50

12. In a fuse, the combination with a primer and means provided with a passage-way substantially empty and directly connecting the primer with the bursting charge and another passage-way containing a slow-burning mass, 60 of hand-operated means for bringing the primer and said means into and out of such a relative position that the directly-connecting passage-way is closed off and the fire-flash coming from the primer passes to the bursting charge through the passage-way containing the slow-burning mass. 65

In testimony whereof I have hereunto set my hand in the presence of two subscribing witnesses.

KARL WIESER.
